UNITED STATES PATENT OFFICE.

IRA ORVILLE WRIGHT, OF BALTIMORE, MARYLAND, ASSIGNOR TO FARLOW DRAFT GEAR COMPANY, OF BALTIMORE, MARYLAND, A CORPORATION OF DELAWARE.

DRAFT AND BUFFING GEAR FOR CARS.

No. 923,398.

Specification of Letters Patent. Patented June 1, 1909.

Application filed April 7, 1908. Serial No. 425,750.

To all whom it may concern:

Be it known that I, IRA ORVILLE WRIGHT, a citizen of the United States, residing at Baltimore city and State of Maryland, have 5 invented new and useful Improvements in Draft and Buffing Gear for Cars, of which the following is a specification.

The object of my invention is the provision of a draft and buffing gear so constructed and arranged that the momentum or *vis viva* of the locomotive or locomotive and cars at the front of the car to which the gear is applied, or of the car or cars at the rear thereof, or of the car itself, will be transformed into the work of compressing springs and moving friction surfaces one upon another, thereby preventing damage to or the destruction of the frame of the car.

The invention consists in certain novelties 20 of construction and the combination of parts hereinafter set forth and pointed out in the claims.

The accompanying drawings illustrate one example of the physical embodiment of the 25 invention constructed and applied according to the best mode I have so far devised for the practical application of the principle.

Figure 1 is a top plan view of a part of the floor frame of one end of a car with the gear 30 applied. Fig. 2 is a vertical longitudinal section of Fig. 1 on line *x*—*x*. Fig. 3 is a section of Fig. 2 on line 3—3. Fig. 4 is a section of Fig. 2 on line 4—4. Fig. 5 is a plan view of the rear follower abstracted from the assembled gear as shown in Fig. 2 and turned to an 35 angle of 90 degrees from the relative position it occupies in Fig. 2 showing the two parts thereof united by the rear key and slightly separated to more clearly illustrate the construction. Fig. 6 shows one of the friction shoes.

Referring to the several figures, the numeral 1 designates the center stringers of a car floor, in this instance consisting of metal- 45 lie channel beams with their flanges extending outwardly; 2, the end sill; 3, a draw bar and coupler of a well known type; 4, a horizontal slot in the draw bar; 5, elongated slots in the webs of the channel beams; 6, slotted 50 cheek plates riveted to the channel beams, the slots therein conforming to the slots in the webs of the channel beams; 7, a front slotted follower block located at the end of the draw bar; 8, a rearwardly projecting friction wedge 55 or extension of the follower block, in this in-

stance integral therewith, and having opposite inclined frictional surfaces 9, 9, the angular disposition of the surfaces to each other depending upon the construction and location of the other parts of the gear with which 60 they coöperate; 10, lugs for supporting and retaining springs in their proper positions; 11, a rear follower consisting of two levers of substantially identical construction and shape, each lever having a hole 12, an arm 13 65 provided with a lug or extension 14 to enter and support a coiled spring, and an arm 15 with a perforated boss 16 having a convex surface 17, as shown; 18, a friction shoe or element having a friction surface 19, a concave seat to receive the boss 16, and two perforated lugs or bosses 20, 20, the perforations 70 being in line with the perforation through the boss 16 at the end of the lever arm; 21, a pin located in the perforations of the bosses 16 75 and 20, the parts being so fashioned that the shoe may have a slight rotary motion about the axis of the pin as a center; 22, draft links, each having three slots or holes, the two slots adjacent the end of the draw bar being elongated; 23, a rear key passed through the rear 80 slots in the webs of the channel beams and cheek plates, the rear slots or holes in the draft links, and through the holes in the two levers, the said key constituting a common 85 fulcrum for the two levers; the same being stationary in buffing and forwardly movable with the follower in drawing; 24, a key passed through the middle slots in the channel beams, cheek plates and draft links, and 90 also through the slot in the front follower block; 25, a front key passed through the front slots in the channel beams, cheek plates and draft links, and also through the slot 4 in the draw bar; 26, a lug upon the front follower 95 block seated within a recess 27 in the end of the draw bar; and 28 designates coiled springs located between the lever arms 13 and the front follower block.

Upon reference to Fig. 5 it will be observed 100 that the ends of the lever arms 13 and 15 are offset at the ends so that the lugs or bosses for supporting the springs, and the shoes will be substantially in the same plane.

The parts being in their normal relative 105 positions, as shown in Figs. 1 and 2, the *modus operandi* is as follows: In drawing the draw bar and coupler, the front key, the rear key, the rear follower and the links move forwardly. The front follower block and 110

middle key are stationary. As the draft links advance they carry with them the rear key 23 and rear follower. As the follower moves forwardly the lever arms 13 bearing 5 against the springs are rotated, which action rotates the lever arms 15 and forces the shoes 18 into frictional contact with the inclined surfaces 9, 9 of the wedge 8 at the rear of the front follower. In buffing the draw bar, 10 front key, front follower block, middle key, and friction wedge move rearwardly. The rear key and draft links are stationary. The arms 13 of the levers are rotated by the pressure of the springs, which action rotates the 15 lever arms 15 and forces the shoes against the inclined surfaces 9, 9 of the rearwardly moving friction wedge.

From the foregoing description taken in connection with the drawings it will be seen 20 that I have provided a gear which attains the end set forth as the object of my invention.

What I claim is:

1. The combination in a draft and buffing gear, of a follower comprising two perforated 25 levers; and a fulcrum pin or bar located within the perforations of the levers; one arm of each lever being provided with a lug to support a spring, and the other arm having a friction surface.
2. The combination in a draft and buffing gear, of a follower comprising two perforated 30 levers; and a movable fulcrum pin or bar located within the perforations of the levers; one arm of each lever being provided with a lug to support a spring, and the other arm having a friction surface.
3. The combination in a draft and buffing gear, of a follower comprising two perforated 35 levers; and a fulcrum pin or bar located within the perforations of the levers; one arm of each lever being provided with means for supporting a spring, and the other arm having a friction shoe.
4. The combination in a draft and buffing 45 gear, of a follower comprising two perforated levers; and a fulcrum pin or bar located within the perforations of the levers; one arm of each lever being provided with means for supporting the end of a spring, and the other arm having a pivoted friction shoe.
5. The combination in a draft and buffing gear, of a follower comprising two perforated 55 levers; and a fulcrum pin or bar located within the perforations of the levers; the arms of each lever being angularly disposed each to the other.
6. The combination in a draft and buffing gear, of a follower comprising two perforated 60 levers; and a fulcrum pin or bar located within the perforations of the levers; one arm of each lever being provided with a lug to support a spring, and the other arm hav-

ing a friction surface, the lugs and friction surfaces being offset.

7. The combination in a draft and buffing 65 gear, of a follower provided with a friction wedge and means for supporting springs; and another follower comprising two levers, one arm of each lever being provided with means for supporting a spring and the other 70 arm having a friction surface to engage the friction wedge.

8. The combination in a draft and buffing gear, of a follower provided with a friction 75 wedge and means for supporting springs; and another follower comprising two levers, one arm of each lever being provided with means for supporting a spring and the other arm having a friction shoe to engage the friction wedge.

9. The combination in a draft and buffing gear, of a follower provided with a friction 80 wedge and means for supporting springs; and another follower comprising two levers, one arm of each lever being provided with means for supporting a spring and the other arm having a pivoted friction shoe.

10. A follower block for a draft and buffing gear having lugs for supporting the ends 85 of springs and a friction wedge.

11. A follower for a draft and buffing gear consisting of two levers, one arm of each 90 having means for supporting a spring and the other arm a friction surface; the said levers being perforated to receive a common 95 fulcrum pin or bar.

12. A follower for a draft and buffing gear consisting of two levers, one arm of each 100 having means for supporting a spring and the other arm a friction shoe; the said levers being perforated to receive a common fulcrum pin or bar.

13. The combination in a draft and buffing gear, of a slotted follower block having 105 a friction wedge; a follower comprising two perforated levers, one arm of each lever having a friction surface and the other arm means for supporting cushioning means; a fulcrum pin or bar; a key; and cushioning means between the followers.

14. The combination in a draft and buffing gear, of a perforated follower block having 110 a wedge; a follower comprising two perforated pivoted levers with friction surfaces to engage the wedge; springs between the 115 followers; keys for the followers; a draw bar; and means connecting the draw bar and rear follower.

In testimony whereof I affix my signature in presence of two witnesses.

IRA ORVILLE WRIGHT.
